Patented Oct. 2, 1928.

Des. 76,484

UNITED STATES PATENT OFFICE.

EDWARD KARFIOL, OF BROOKLYN, NEW YORK.

DESIGN FOR DOILY.

Application filed July 18, 1928. Serial No. 27,515. Term of patent 14 years.

To all whom it may concern:

Be it known that I, EDWARD KARFIOL, a citizen of the United States, residing in Brooklyn, in the county of Kings and State of New York, have invented a new, original, and ornamental Design for Doily, of which the following is a specification, reference being made to the accompanying drawing, forming part thereof, in which the figure represents a face view of a doily showing my new design.

The full lines of the drawing show one-quarter of the design in detail and the full line about the circumference is a continuation of the border, the dotted circular lines are continuation of the outline of the plain portion of the centre of the doily.

I claim:

The ornamental design for doily as shown and described.

EDWARD KARFIOL.
